UNITED STATES PATENT OFFICE.

BARNETT GERSHOVITZ AND HARRY AXELROD, OF CANTON, OHIO.

DEVICE FOR EXTRACTING SPOKES.

1,151,006.

Specification of Letters Patent. Patented Aug. 24, 1915.

Application filed December 8, 1914. Serial No. 876,041.

To all whom it may concern:

Be it known that we, BARNETT GERSHOVITZ and HARRY AXELROD, subjects of the Czar of Russia, residing at Canton, in the county of Stark and State of Ohio, have jointly invented a new and useful Device for Extracting Spokes, of which the following is a specification.

Our invention relates to a device for extracting spokes and is more specifically a manually operated device for removing old, worn or damaged spokes from wheel hubs when it is necessary to replace the same with new spokes.

15 The object of our invention is to provide a simple, durable and easily operated device for removing spokes from wagon wheels.

20 A further object is to provide a device of this character which may be easily and readily adjusted to any size of wheel or spoke.

25 With these objects in view the invention consists in the novel construction and arrangement of parts, hereinafter described, illustrated in the accompanying drawings, and particularly pointed out in the appended claims, it being understood that various changes in the form, proportion, size and minor details of construction may be made within the scope of the appended claims 30 without departing from the spirit or sacrificing any of the advantages of the invention.

35 In the drawings: Figure 1 is a front elevation of our device showing the means of using the same. Fig. 2 is a side elevation of the same. Fig. 3 is a detail perspective view of the sliding jaws which engage the spokes. Fig. 4 is a detail perspective view of the stirrup which is carried by the sliding 40 jaw.

Similar numerals of reference indicate corresponding parts throughout the several figures of the drawing.

45 Referring more specifically to the construction illustrated in the accompanying drawings, the numeral 1 indicates a block to which is attached a pair of legs 2, each of which is provided with an offset portion 3 extending over the greater portion of its 50 length and bridged across by a guide plate 4 connected at either extremity by means of a rivet 5 or its equivalent. A foot 6 is provided upon the free extremity of each of the legs 2, said foot being provided with a concaved face 7 adapted to contact with the hub 55

of a wheel, Fig. 1 of the drawings showing the feet on the hub A shown in dotted lines. At a point near the feet 6 an arched tie-bar 8 connects the two legs 2 and is attached thereto by means of rivets 9, a similar tie-bar 10 being located opposite the tie-bar 8 and connecting the two guide plates 4, being attached thereto by means of rivets 11 or their equivalents.

60 A screw threaded stem 12 is located through the internally threaded aperture 13 in the block 1 and is provided at its outer extremity with a suitable hand wheel 14 which is rigidly connected thereto by any suitable and well known means such as the set screw 15. The inner extremity of the stem 12 is reduced at 16 and is rotatably mounted within the aperture 17 located in the head 18 of the sliding jaws, a collar 19 being placed upon the reduced portion 16 and attached thereby by means of a pin 20.

65 The jaws 21 and 22 which are adapted to grip the spoke are pivoted to the head 18 by means of bolts 23 and 24, respectively, said jaws being provided at their free extremities with teeth 25. Teeth 26 may also be provided upon the jaws at a point intermediate their ends. A stirrup 27 is located around the jaws 21 and 22 and provided with a central arched portion 28. One extremity of the stirrup is reduced at 29, and adapted to slide upon one of the legs 2 and is provided with apertures 30 through which a bolt 31 is passed, said bolt connecting the stirrup to the jaw 21 by means of the eye 32 in said jaw, the opposite extremity 33 of the stirrup being squared and slidably mounted between the opposite leg 2 and the guide plate 4 and provided with an internally screw threaded aperture 34. A curved 75 leaf spring 35 is connected to the jaw 21 by means of rivets 36 and has its free end resting upon the jaw 21, said spring contacting with the adjacent leg 2 intermediate its ends, tending to hold the jaw 21 in contact with the spoke B shown in dotted lines Fig. 1; a U-shaped spring 37 is also attached to the jaw 21 by means of the rivets 36 and its free end contacting with the inner face of the jaw 22 tending to hold the two jaws apart. 80

85 Suitable guide flanges 38 are provided upon the outer face of the jaw 22 for the purpose of maintaining the stirrup 27 in alignment and a screw threaded stem 39 is located through the internally threaded aperture 34 90 95 100 105 110

in the square portion 33 of the stirrup, the inner extremity of the screw threaded stem contacting with the jaw 22, a suitable hand wheel 40 being provided upon the outer end 5 of the stem 39.

When it is desired to remove a spoke from the wheel the device is first placed in the position upon the wheel as shown in Fig. 1 and the hand wheel 40 is rotated drawing 10 the jaws 21 and 22 together, the teeth 25 and 26 upon said jaws tightly gripping the spoke between them. The hand wheel 14 is then rotated, moving the sliding jaws toward the block 1 and drawing the spoke B 15 out of the socket in the hub A.

Although the drawings and above specification disclose the best mode in which we have contemplated embodying our invention we desire to be not limited to the details of 20 such disclosure, for, in the further practical application of our invention, many changes in form and construction may be made, as circumstances require or experience suggests, without departing from the spirit of 25 the invention, within the scope of the appended claims.

We claim:

1. In a device of the character described, the combination with a frame comprising a 30 block and legs provided with feet, each of said legs being provided with an off-set portion and a guide plate bridging said off-set portion, of a screw threaded stem mounted within said block, a hand wheel located 35 upon the outer extremity of said screw threaded stem, a head carried upon the inner end of said screw threaded stem, jaws pivotally mounted upon said head, teeth located upon the inner faces of said jaws, a 40 stirrup pivotally connected to one of said jaws, one extremity of said stirrup being located around one of said legs, the opposite extremity of said stirrup being provided with a square shank slidably mounted between the leg of said frame and the guide 45 plate carried thereby, a screw threaded stem mounted within said squared shank, the inner extremity of said stem contacting with one of said jaws, a hand wheel mount-

ed upon said stem and means for normally holding said jaws apart.

2. In a device of the character described, the combination with a frame consisting of a block and two legs, of a screw threaded stem mounted within said block, a head carried upon the inner extremity of said stem, jaws pivoted upon said head, a spring located between said jaws adapted to normally hold said jaws apart, a second spring 55 located between one of said jaws and the adjacent leg, said second named spring adapted to normally hold said jaw away from said leg, a stirrup carried by said jaws and slidably mounted upon said legs and means carried by said stirrup for closing said jaws. 60

3. In a device of the character described, the combination with a frame comprising a block and legs provided with feet, each of said legs being provided with a longitudinal slot, of a screw threaded stem mounted within said block, a hand wheel located upon the outer extremity of said screw threaded stem, a head carried upon the inner extremity of said screw threaded stem, jaws pivotally mounted upon said head, 70 one of said jaws provided with a lateral perforation, a stirrup pivotally connected to said jaw by means of a pin passing through said lateral perforation, one extremity of said stirrup being located around one of 75 said legs, the opposite extremity of said stirrup being provided with a square shank, slidably mounted within the slot of the other of said legs, a screw threaded stem mounted within said squared shank, the inner extremity of said stem contacting with one of said jaws, and a spring located between said jaws for normally holding said jaws apart. 80

In testimony that we claim the above, we 90 have hereunto subscribed our names in the presence of two witnesses.

BARNETT X *GERSHOVITZ*
mark

HARRY AXELROD.
